CLAIM

The ornamental design for the folding multipurpose hand tool, as shown and described.

DESCRIPTION

FIG. 1 is a perspective view of a folding multipurpose hand tool showing my new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is another left side elevation view thereof with a saw portion in a partially folded position;

FIG. 9 is yet another left side elevation view thereof with a saw portion and a knife portion in partially folded positions;

FIG. 10 is yet another left side elevation view thereof with a saw portion and a knife portion in folded positions and a gut hook portion in an extended position;

FIG. 11 is a perspective view of a modified embodiment of the folding multipurpose hand tool;

FIG. 12 is a right side elevation view thereof;

FIG. 13 is a left side elevation view thereof;

FIG. 14 is a top plan view thereof;

FIG. 15 is a bottom plan view thereof;

FIG. 16 is a front elevation view thereof;

FIG. 17 is a rear elevation view thereof;

FIG. 18 is another left side elevation view thereof with a saw portion in a partially folded position;

FIG. 19 is yet another left side elevation view thereof with a saw portion and a knife portion in partially folded positions; and,

FIG. 20 is yet another left side elevation view thereof with a saw portion and a knife portion in folded positions and a gut hook portion in an extended position.

The broken lines shown herein are for illustrative purposes only and form no part of the claimed design.
